FOLDING CANOPY FOR CASKETS.

APPLICATION FILED OCT. 1, 1904.

2 SHEETS—SHEET 2.

Inventor:

Charles E. Richards

By Luther L. Miller,
Atty.

UNITED STATES PATENT OFFICE.

CHARLES E. RICHARDS, OF CHICAGO, ILLINOIS.

FOLDING CANOPY FOR CASKETS.

SPECIFICATION forming part of Letters Patent No. 789,565, dated May 9, 1905.

Application filed October 1, 1904. Serial No. 226,873.

To all whom it may concern:

Be it known that I, CHARLES E. RICHARDS, a citizen of the United States, residing at Chicago, in the county of Cook and State of Illinois, have invented certain new and useful Improvements in Folding Canopies for Caskets, of which the following is a specification.

Canopies for caskets as heretofore constructed have been formed by hinging a board upon the under side of the cover of the casket and attaching the canopy-draperies to the edges of said board. When the casket-cover bearing such a canopy was opened into a vertical position, the canopy-board was swung outwardly horizontally and secured, the draperies hanging from the edges of said canopy-board. Such canopies are cumbersome and unwieldy and the objections to them are numerous. For instance, it is extremely difficult to secure the board in a horizontal position. When the board is folded against the cover, the canopy-draperies must be tucked behind the board, in which position they are hidden from view, and, furthermore, soon become mussed and disordered, and the canopy-board must be made with and as a part of the casket, necessitating carrying in stock a line of caskets fitted with canopies, as well as those without canopies.

The object of this invention is the production of a light collapsible canopy that shall overcome the objections mentioned—that is to say, a canopy that may readily be applied to any ordinary casket having a swinging cover and as readily removed therefrom, that is adjustable within reasonable limits to caskets of different lengths, that folds into small compass either in the casket or in shipping it separately therefrom, and in which when folded the canopy-draperies hanging against the casket-cover materially enhance its beauty.

A further object of this invention is the production of a canopy which is lighter, cheaper, and more easily operated than the canopy now in use.

In the accompanying drawings, Figure 1 is a perspective view of a casket, showing my improvements applied thereto. Fig. 2 is a

top plan view, partly in section, of the canopy-frame extended, the dotted lines in said figure 50 showing it in a folded position. Fig. 3 is a transverse vertical section through a casket, showing the canopy open. Fig. 4 illustrates one of the brackets by means of which the canopy is secured to the inner side of the 55 cover of the casket. Fig. 5 is a transverse section through one of the side arms of the canopy-frame on dotted line 5 5 of Fig. 2, showing the wooden attaching-strip in position. Fig. 6 is a transverse view through 60 one of the clamping-clips on the front rails of the canopy-frame, taken on dotted line 6 6 of Fig. 2. Fig. 7 is a longitudinal sectional view through the hinge connection between the outer ends of the side arms and the front 65 rails. Fig. 8 is a longitudinal section through the middle hinge of one of the side arms of the canopy-frame, illustrating the means employed for limiting the movement of said hinge. Fig. 9 is a longitudinal sectional view 70 through the hinge-joint connecting the brackets and the side arm.

In the drawings, A refers to an ordinary casket, and B to the cover, secured thereto by the usual stop-hinges.

75

In the construction of a canopy embodying the features of my invention I provide a supporting-framework rectangular in general outline and comprising the jointed side arms 2 and the longitudinally-adjustable front rails 80 3. The side arms 2 comprise two links 4 and 5, connected together at their adjacent ends by means of a pivot 6, the links 5 being provided with overlapping fingers 7 for engaging the inner faces of the arms 4, and thus 85 limiting the outward pivotal movement of said links. At their inner ends the links 4 are pivotally connected with clip-pieces 8, each provided upon one of its faces with radial ratchet-teeth 9, centrally perforated 90 and internally screw-threaded to receive a thumb-screw 10. Two brackets 11 are secured upon the inner side of the casket-cover B, as by screws passing through openings 12 in said brackets. Each of the brackets 11 is 95 provided with a projecting ear 13, centrally

perforated to receive the thumb-screw 10, and upon its outer face said ear is provided with a tooth or projection 14, adapted to lie within one of the notches formed between the 5 ratchet-teeth 9. The pivotal movement of the links 4 with relation to the pieces 8 is limited by means of stop-fingers 15 upon each of said pieces, adapted to engage the outer side of the links 4 in the pivotal movement of said 10 links. The outer end of each of the links 5 is pivotally connected with a member 16 by means of a pin 17, said member 16 and links 5 being provided with interlacing fingers 18 to strengthen the pivotal joint between them 15 and to limit the outward movement of said links 5.

The front rails 3 are secured rigidly within the member 16 by rivets or other suitable means. Said front rails are overlapped for 20 a portion of their length, each being provided with a tightening-clip 19 and a bolt 20. The sides of each clip 19 extend over the edges of the two rails 3, and the bolt 20 extends through a circular opening 21 in one of said 25 rails and an elongated opening 22 in the other rail. By this means a considerable longitudinal adjustment of the frame is made possible.

In order to form a support for the tacks by means of which the draperies of the canopy 30 are secured to the frame, I provide wooden strips 23, fastened in any suitable manner, as by screws, (not shown,) to the outer faces of the front rails 3 and of the side arms 2. The draperies properly arranged are secured to 35 the frame, said draperies comprising looped portions 24 and 25 of a fabric forming such draperies.

26 is a loop attached to the front rails 3, and 27 is a stud or hook fixed to the casket-40 cover B, over which stud the loop 26 is intended to be placed to hold the canopy-frame in its folded position when the casket-cover is to be closed.

In fitting my improved canopy to a casket 45 the canopy-frame is adjusted in length by loosening the bolts 20 and adjusting the length of the front rails 3 to suit the length of the casket. The brackets 11 are secured upon the inner face of the casket-cover B either 50 upon the flat surface of said cover or upon the beveled or inclined portion thereof. The arms 2 are then attached to said brackets 11 by means of the thumb-screw 10, said arms being held in a position at right angles with 55 said cover by adjustment with relation to the brackets 11. Wooden strips 23 having been secured to the front rails 3, the draperies are attached to the canopy-frame and the cover B. When the canopy is in use, the frame is 60 drawn outward into the position indicated in Fig. 1. When the canopy is folded, it occupies the position indicated by dotted lines in Fig. 2.

My invention is not restricted to the particular construction and arrangement of the 65 parts herein shown, as such construction and arrangement may be changed or modified by those skilled in the art without departing from the spirit and scope of the invention.

I claim as my invention—

1. A canopy for caskets comprising a hinge-jointed collapsible frame and means for securing said frame to the casket.
2. In a canopy for caskets, in combination, a collapsible frame comprising an extensible 75 front rail; and means for securing said frame to the casket.
3. In a canopy for caskets, in combination, a collapsible frame; means for securing said frame to the cover of the casket; and means 80 for adjusting the angular position of the frame with relation to said cover.
4. In a canopy for caskets, in combination, a canopy-frame; means for securing said frame to the cover of the casket; means for adjusting the angular position of said frame with 85 relation to said cover.
5. In a canopy for caskets, in combination, a canopy-frame comprising a front rail and two side arms pivotally connected with said 90 front rail; and means for securing said frame to the cover of the casket.
6. In a canopy for caskets, in combination, a canopy-frame comprising a front rail and two side arms, each foldable together upon 95 itself, which side arms are pivotally connected with said front rails; and means for securing said frame to the cover of the casket.
7. In a canopy for caskets, in combination, a canopy-frame comprising a front rail and 100 two side arms pivotally connected with said front rail; means for securing said side arms to the cover of the casket; and means for adjusting the position of said frame with relation to said cover.
8. In a canopy for caskets, in combination, a canopy-frame comprising an adjustable two-part front rail and two side arms pivotally connected with said front rail; and means for securing said frame to the cover of the casket. 110
9. In a canopy for caskets, in combination, a canopy-frame comprising an adjustable two-part front rail and two side arms pivotally connected with said front rail; a tightening-clip for said front rail; brackets for securing 115 said side arms to the cover of the casket; and means for adjusting the angular position of the canopy-frame with relation to said brackets.
10. In a canopy for caskets, in combination, 120 a canopy-frame comprising a front rail and two folding arms pivotally connected with said front rail; and means for pivotally connecting said arms with the cover of the casket.
11. In a canopy for caskets, in combination, 125 a canopy-frame comprising a front rail ad-

justable in length and two folding arms pivotally connected with said front rail; and means for pivotally connecting said arms with the cover of the casket.

5 12. In a canopy for caskets, in combination, a folding metallic frame; means for securing said frame to the cover of the casket; and

wooden drapery-attaching strips connected with said frame.

CHARLES E. RICHARDS.
